[57] CLAIM

The ornamental design of a combined toy boat and container for writing instruments, as shown and described.

DESCRIPTION

FIG. 1 is a top right front perspective view of a combined toy boat and writing instrument container showing our new design;

FIG. 2 is the top plan view thereof;

FIG. 3 is a right side elevational view thereof;

FIG. 4 is a left side elevational view thereof;

FIG. 5 is the bottom plan view thereof;

FIG. 6 is the rear elevational view thereof;

FIG. 7 is the front elevational view thereof; and,

FIG. 8 is an exploded top right front perspective view thereof. The broken lines showing the writing instruments are for illustrative purposes only and form no part of the claimed design.
